[57] CLAIM

We claim the ornamental design for a bottle, as shown.

DESCRIPTION

FIG. 1 is a perspective view of the bottle design;
FIG. 2 is a top plan view of the bottle design;
FIG. 3 is a bottom plan view of the bottle design;
FIG. 4 is a front elevational view of the bottle design; and,
FIG. 5 is a right side elevational view, with the left side view being a mirror image thereof of the bottle design.
